(57) **CLAIM**

The ornamental design for a stand for monitor, as shown and described.

DESCRIPTION

FIG. 1 is a perspective view of a stand for monitor showing the new design;

FIG. 2 is a front view thereof;

FIG. 3 is a rear view thereof;

FIG. 4 is a left side view thereof;

FIG. 5 is a right side view thereof;

FIG. 6 is a top view thereof;

FIG. 7 is a perspective view showing the article supporting a monitor in a high position; and,

FIG. 8 is a perspective view showing the article supporting a monitor in a low position.

The broken line showing of a monitor is included for the purpose of illustrating environment and forms no part of the claimed design.

1 Claim, 8 Drawing Sheets
